UNITED STATES PATENT OFFICE.

KAZIMIERZ SULEK, OF THORPE, WEST VIRGINIA.

TOILET IMPLEMENT.

1,409,979.

Specification of Letters Patent. Patented Mar. 21, 1922.

Application filed October 5, 1921. Serial No. 505,492.

To all whom it may concern:

Be it known that I, KAZIMIERZ SULEK, a citizen of Poland, residing at Thorpe, in the county of McDowell and State of West Virginia, have invented certain new and useful Improvements in Toilet Implements, of which the following is a specification.

The salient object of the invention is to provide a compact and comparatively simple 10 toilet implement in which the various parts cannot be misplaced.

Other objects and advantages will appear in the following description, taken in connection with the drawing and forming a 15 material part of the disclosure, in which:—

Figure 1 is a front elevational view of a toilet implement made in accordance with the invention.

Figure 2 is a side elevational view of the 20 same.

Figure 3 is a fragmentary view with certain parts in operative position.

Figure 4 is a fragmentary perspective view of the same with the cover removed 25 and the various parts in other position.

Referring to the drawings, the numeral 10, represents a backing member carrying brush tufts 11 on one side and in the opposite face is framed a mirror 12, retained in position 30 by an annular ring 14 secured by screws 15.

The backing member 10, at its lower extremity, forms a handle 17 containing a recess 19 and a cover 18 over the recess, secures 35 between itself and the handle body 17 a hair comb 20 and a button hook 21.

The comb may be placed in a usable position, either by inserting the thumb nail into a groove 22 and rotating the comb on the pivot 24 until it is in a position as shown in 40 Figure 3, or by pressing on the handle end 25 of slidable rack 26, the screw 27 and slot 28 permitting this slidable movement. The rack engaging with the segmental gear 30

on the pivoted end of the comb 20, it is readily seen that the comb 20 will swing in an 45 arc about its pivot 24 into the position shown in Figure 3.

In the same manner the comb 20 may be returned to its housed position by pulling the handle end 25 of the rack 26. 50

The button hook 21 may be placed in operative position by applying the fingers at 31 and rotating the button hook on its pivot 32.

The pivots 24 and 32 may be made so as to form securing members for the cover 18 55 to the handle 17.

Although the foregoing is descriptive of the preferred embodiment of this device, it is understood that changes in the form, arrangements, proportions, sizes and details 60 may be made without conflicting with the scope of the invention as defined in the appended claims.

Having thus described my invention, what I claim as new and desire to secure by Letters Patent, is:—

1. In a toilet implement, in combination with a backing plate having brush tufts on one face and a mirror on the opposite face, said plate having a recess at one end, of a 70 comb pivoted in the mentioned recess, at the outer end thereof, a bar slidably longitudinally in said plate adjacent the recess, a head on said bar by which it may be operated, teeth on one edge of said bar, and means on 75 the pivotal end of said comb co-operative with said teeth whereby said comb may be rotated into operative position.

2. In a toilet article, a backing plate having a recess at one end, a comb pivoted in 80 the mentioned recess, a segmental gear at one end of said comb, a sliding rack engaging said gear, and means for guiding said rack.

In witness whereof I affix my signature. 85
KAZIMIERZ SULEK.
